UNITED STATES PATENT OFFICE

PAUL T. FRANKL, OF NEW YORK, N. Y., ASSIGNOR TO CELLULOID CORPORATION, A CORPORATION OF NEW JERSEY

DESIGN FOR A TOILET-ARTICLE HOLDER OR SIMILAR ARTICLE

Application filed December 22, 1928. Serial No. 29,379. Term of patent 3½ years.

To all whom it may concern:

Be it known that I, PAUL T. FRANKL, a citizen of the United States, residing at New York, in the county of New York, and State of New York, have invented a new, original, and ornamental Design for a Toilet-Article Holder or Similar Article, of which the following is a specification, reference being had to the accompanying drawing, forming part thereof.

Figure 1 is a plan view of a toilet article holder or similar article, showing my new design.

I claim:

The ornamental design for a toilet article holder or similar article, as shown.

PAUL T. FRANKL.
